United States Patent Office

Des. 191,009
Patented Aug. 1, 1961

191,009

DYNAMOMETER

Thomas B. Martin, P.O. Box 392, Danville, Calif.

Filed Jan. 23, 1961, Ser. No. 63,655

Term of patent 14 years

(Cl. D52—6)

Fig. 1.

Fig. 2.

Fig. 3.

FIG. 1 is a top plan view of a dynamometer showing my new design.

FIG. 2 is a side elevation.

FIG. 3 is a bottom view thereof.

The opposite side of FIG. 2 is substantially the same in appearance as the side shown.

I claim:

The ornamental design for a dynamometer, as shown and described.
